By Marcus Clark, M.M.

UNITED STATES PATENT OFFICE.

GUSTAVE CHARLES MOREUX, OF LEVALLOIS-PERRET, FRANCE, ASSIGNOR TO SOCIÉTÉ EN NOM COLLECTIF G. MOREUX & CIE., OF LEVALLOIS-PERRET, FRANCE, A FRENCH COMPANY.

RADIATOR CONSTRUCTION.

Application filed March 20, 1925, Serial No. 17,041, and in France October 2, 1924.

Radiators for motor vehicles are known in which the cooling block and its water tanks are concealed by a removable radiator case, the upper opening of which fits over the filling tube. Usually, the inner part of this radiator case forms a rest for the hood of the vehicle and carries, for forming a joint and deadening the vibrations, a felted lace. Now, it is noted, in practice, especially when conical hoods are used, that this bearing surface is not sufficient, for efficiently maintaining the corresponding edge of the hood.

The present invention is adapted to remedy these inconveniences without necessitating the modification of existing radiator cases. It essentially consists in extending the rest for the hood, formed by these latter by means of a supplementary surface carried by the radiator. This surface forms therefore a kind of hood or frame which passes over the upper water tank and is secured on the partitions staying the water tanks of the radiator; this surface is transversely shaped in such a manner as to extend the corresponding surface of the radiator case which bears, on the other hand on the said surface and can be secured on a frame which is attached to the longitudinal bearers of the chassis for receiving the radiator.

In the accompanying drawing and by way of example:

Fig. 1 illustrates in vertical section a radiator provided with a removable case, constructed in accordance with the improvement forming the subject-matter of the invention.

Fig. 2 is a corresponding horizontal half-section thereof.

Figs. 3, 4 and 5 illustrate another form of construction.

As indicated in the foregoing, the radiator is covered in the known manner with a removable radiator case, the upper opening of which fits over the tube *b* used for filling up the cooling block. This radiator case *a*, which carries the hinge *c* of the hood, extends rearwardly in a bearing surface *d* carrying, as usual, a lacing for deadening the vibrations.

According to this invention, in order to

increase this bearing surface for the hood without having to modify the radiator case, on the radiator is mounted a frame or hoop *e* which passes over the upper water tank *f* and is secured on the vertical partitions *g* staying the water tanks, as well as the securing members *h* of the radiator. The cross section of this ring or hoop *e* is bent, so that one of its parts *i* can receive and support the corresponding edge of the radiator case *a*, the other part *j* forming an extension of the said edge so as to increase to the desired extent the bearing surface of the hood. The part *j* is provided with a lacing as the corresponding edge of the radiator case with which it is combined.

In the constructional modification illustrated in Figs. 3, 4 and 5, the supplementary surface *e* (which is to extend the rest of the removable radiator case *a* for serving as a bearing for the engine hood) is mounted on a rigid frame *k*.

This frame *k* is attached to the longitudinal bearers of the chassis of the vehicle, by means of side members *k*¹, for instance, and receives the radiator which is assembled with it. This frame *k* forms also a bearing for the corresponding ledge of the radiator case *a*.

By way of example, this frame *k* is constituted by a sheet iron plate *m* in U shape. On the said frame *k* is secured the frame or hoop *e* and bears on the inner ledge of the removable radiator case *a*.

The upper water tank *f* (Fig. 2) of the radiator and the side partition staying the water tank of the latter, fit into the frame *k*. The angle iron *l* carried by the radiator forms an abutment for limiting its sinking in the supporting frame *k*. The radiator can be secured in any suitable manner and the side securing members of the radiator can be superposed to the securing members *k*¹ of the frame *k*, so as to be secured on the frame by means of the same securing bolts.

The removable radiator case *a* is secured by the plug of the radiator and by two side bolts *n* taking a bearing on the frame *k*.

Besides the large bearing surface thus obtained for the hood, it will be seen that this frame *k* (which preserves the radiator from

the distortions of the chassis and, from this fact, increases the strength) allows to send the vehicle to the painting shop for instance, without the radiator or the radiator case being placed in position. However, the hood can be placed in position, since it has a bearing on the frame *k* rigid with the chassis. This is of great interest in case of a manufacture in series.

10 It is obvious that the frame *k* considered in itself forms a part of the invention, even if it is not provided with the supplementary surface, which must form an extension of the rest of the removable radiator case *a*.

15 What I claim as my invention and desire to secure by Letters Patent is:—

1. In a motor vehicle, a chassis, a radiator, a vertical frame at the front of said chassis and disposed rearwardly of said radiator, 20 a case for said radiator, and a hood, said frame being adapted to support the hood and case.

2. In a motor vehicle, a chassis, a radiator, a vertical frame at the front of said chassis and disposed rearwardly of said radiator, a 25 case for said radiator, and a hood, said frame being offset and the offset portions thereof being adapted to respectively support the case and hood.

3. In a motor vehicle, a chassis, a radiator, a vertical frame fastened to the front of the 30 said chassis behind the radiator, and having a projection at the rear thereof for receiving a lacing, the said radiator being 35 enclosed in the said frame and secured to the same, a case for the radiator supported by the frame and provided with an upper aperture for a filling pipe on the radiator, fastening lugs on the said case, a depressed 40 part on the rear edge of the case, a lacing on the projection of the said case, in order to support a hood.

In testimony whereof I have signed my name to this specification.

45 GUSTAVE CHARLES MOREUX.
